UNITED STATES PATENT OFFICE.

LAWRENCE H. DICKELMANN AND JOHN KUCHLER, OF MILWAUKEE, WISCONSIN.

PIPE-CLIP AND METHOD OF FORMING SAME.

1,329,268.

Specification of Letters Patent.

Patented Jan. 27, 1920.

Application filed March 5, 1919. Serial No. 280,816.

To all whom it may concern:

Be it known that we, LAWRENCE H. DICKELMANN and JOHN KUCHLER, a citizen of the United States and a citizen of the German Republic, respectively, and residents of Milwaukee, in the county of Milwaukee and State of Wisconsin, have invented certain new and useful Improvements in Pipe-Clips and Methods of Forming Same; and we do hereby declare that the following is a full, clear, and exact description thereof.

Our invention relates to new and useful improvements in clips for securing pipes or other members to a support, more particularly of that type including a body portion adapted to embrace the member to be secured, and having prongs bent therefrom to be driven into the support, our invention residing in the method of forming the clip, as well as in certain advantageous structural features thereof.

It is primarily the object of our invention to provide a clip of this character which is stamped from a single blank of sheet metal, and wherein portions are so arranged as to effect a bracing action procuring an increased strength of the clip.

More particularly, it is our object to provide a clip of this character having securing prongs bent therefrom and formed of a double thickness of metal to procure an increased gripping action in the support in which they are driven, to provide increased strength, and further effecting an arrangement wherein the added thickness of metal forms a brace at the juncture of the prong with the body of the clip.

A further object resides in the provision of a method of forming the clip wherein notches for the sides of the double thickness prongs are formed incidental to stamping out the body blank of the clip.

With the above and other objects and advantages in view, which will be apparent as the description proceeds, our invention resides in the novel features of construction, combination and arrangement of parts as hereinafter more particularly described and defined by the appended claims.

50 In the accompanying drawings:

Figure 1 is a side elevational view of a clip embodying our invention.

Fig. 2 is an end elevational view of the clip.

55 Fig. 3 is a plan view of a blank from which our improved clip is formed, and

showing the first step in the method of making the clip.

Referring now more particularly to the accompanying drawings, our improved clip in its finished shape comprises a bowed and longitudinal ribbed intermediate body section 5, from the ends of which extend outwardly bent support abutting end sections 6 having prongs 7 projecting from their outer portions for engagement in the support to which it is desired to secure the clip, said prongs being each formed of a double thickness of metal integrally connected along one side edge of the prong.

The first step in our method of forming the clip is to stamp the body blank thereof as shown in Fig. 3 from a sheet of metal. In this body blank, it is noted that the outer portions of the end sections 6 are reduced whereby their juncture with the prong blank portions is of considerably lesser width than the general width of the end and intermediate sections and the inner and outer side portions *a* and *b* respectively of the prong blanks are adapted to be bent on the longitudinal line *c*, the inner end of the outer prong side portion affording the connection with the end sections, while the inner end of the inner side portion *a* is free from such connection, being however substantially in alignment with the bending line of the connection. The free edges of the prong side portions are provided with corresponding series of notches *d*. The blank is then placed in the press to afford the bowed and rib shape of the intermediate section, and the prong blanks are bent to project at right angles from the end sections 6. The final step is to bend the prong blanks on the lines *c* to dispose their sides in abutting relation forming the double thickness of the prongs, thus disposing the inner end of the prong side portion *a* in abutting engagement with the under faces of the end sections 6 to afford braces for the prong sections preventing inward bending movement thereof past right-angular relation to the end sections.

At the same time, the notches *d* of the prong sides are brought into registry and thus the complete clip is afforded in a manner avoiding the necessity of any cutting operations subsequent to the initial stamping out step.

In some instances, it may be desired to afford additional securing means for the clip and to this end, the end sections are provided with apertures 8 for the reception

of screws, nails or the like. It may in still other conditions, such as in attaching the clip to a plastered surface, not be desirable to utilize the prongs at all, and in this event 5 the prongs may be bent outwardly and broken off, which may be most readily effected by the single thickness of metal connecting them with the body.

While we have shown and described a preferred embodiment of our invention, it will 10 be appreciated that to meet differing conditions, various changes and modification of structure and operative steps may be employed without departing in any manner 15 from the spirit of our invention.

What is claimed is:

1. A clip of the class described including a bowed body section, end sections extending from the ends of said body section and 20 disposed in a common plane, and prongs extending from the outer portions of the end sections, the cross sectional areas of the 25 prongs at their points of juncture with the end sections being less than other cross sectional areas of the prongs, the metal of said prongs being bent longitudinally to afford double thickness for the prongs.

2. A clip formed of sheet metal and com-

prising a bowed body section, end sections 30 extending from the ends of the body section, and prongs bent from the ends of the end sections, the metal of said prongs being bent longitudinally to form inner and outer side portions, the inner ends of the inner prong side portions abutting the end sections to 35 brace the prongs.

3. The method of forming a clip which consists in stamping out a body blank having prong portions extending from the ends thereof and in simultaneously cutting 40 notches in the sides of the prong portions adapted to register and in then bending said prong portions together longitudinally whereby to form double thickness prongs and to dispose the notches of the side portions of each prong in registry, and bending 45 the body blank to form the clip and bending the prong portions to project at right angles from the adjacent portions of the body.

In testimony that we claim the foregoing we have hereunto set our hands at Milwaukee, in the county of Milwaukee and State of Wisconsin.

LAWRENCE H. DICKELMANN.
JOHN KUCHLER.
